[57] ABSTRACT

A continuous casting plant for the production of slabs, comprising a straight, vertical mould which is water-cooled and releasably mounted in a frame, a secondary cooling or bar guiding means arranged below said mould and including a vertical part with a bending zone which is adapted to be lifted in and out in vertical direction through the frame after the mould has been lifted out of the frame, and a curved part which is adapted to be displaced in horizontal direction, and means for drawing and bending said bar, which are designed as a combined pulling, straightening and rolling stand adapted to be displaced in and out as an individual constructional unit. This plant affords the advantages of a low construction height, and of high operational safety. The quality of the products is improved because the occurrence of cracks is avoided and the bar may solidify symmetrically. Furthermore this plant may be built into existing steel works.

CONTINUOUS CASTING PLANT FOR SLABS

This is a continuation, of application Ser. No. 39,479 filed May 21, 1970, now abandoned.

The invention relates to a continuous casting plant for slabs comprising a straight, vertical mould which is mounted in frame and water-cooled, secondary cooling or bar guiding means arranged below said mould and adapted to be lifted in and out and including a vertical part with a bending zone and a curved part, and means for drawing and bending the bar.

There are various difficulties in casting to slabs which are about 1,000 to 2,000 mm broad and about 140 to 250 mm thick, which difficulties are due primarily to the construction of the plants and to metallurgical factors. Vertical plants in which the bar leaves the mould vertically in downward direction and is vertically passed on and shorn to length in vertical position after its solidification have a great construction height, as a rule they cannot be built into existing steel works and they are very expensive. It has, therefore, been proposed to employ plants with a curved mould and a post-positioned curved bar guide so as to reduce the construction height of the plants and to permit a horizontal delivery of the solidified bar. However, it is difficult to manufacture curved moulds and, apart from that, they entail metallurgical disadvantages as the casting stream impairs the formation of the casting shell and a uniform and symmetrical solidification and segregation in the bar, respectively. In the production of billets and less sensitive steel qualities these difficulties have been partly eliminated but slabs of large dimensions can hardly be produced in a satisfactory manner in such curve-type plants.

In another type of continuous casting plant the bar leaves a vertical, straight mould, it is then further cooling in a comparatively long straight guiding section, at the end of which it is seized by a pulling stand, deflected and finally guided by means of a straightening stand into horizontal position; this means that in this embodiment the solidified bar is bent from vertical position into horizontal position. In such plants some of the metallurgical disadvantages present in the curved plant may be avoided but the costs for the construction are considerable and it is very difficult to build such plants into existing steel works.

In a further type of continuous casting plant the bar, on leaving a vertical mould, is guided through a relatively short, straight guiding section and bent in a bending zone in steps and progressively in a manner that no inadmissible stresses will occur at the surface of the bar. The bar then is further cooled in a curved guide at the end of which it is seized by a pulling stand and straightened. Although this embodiment avoids some of the metallurgical disadvantages of a curved plant, it does not guarantee and avoidance of cracks below the surface and in the vicinity of the solidification front.

The invention is aimed at creating a continuous casting plant for slabs in which the metallurgical disadvantages of known plants are avoided and which has a low construction height.

It is a further aim of the invention to construct the plant by employing pre-fabricated construction units or elements which may easily be exchanged.

In a known construction the secondary cooling zone or bar guiding means, respectively, is mounted to be rotatable; for moving it out the means merely has to be swung and driven out. However, the construction is not

suitable for great plants in which the bar guiding means has to be made of several individual parts. It would be far too expensive to provide for each individual part to be rotatable and capable of being driven out so that such a construction would hardly be feasible.

Further aims of the invention are to create a plant with high operational safety and which permits of "continuous continuous casting". Also it is aimed at improving the metallurgical quality of the products.

10 The plant according to the invention is characterized in that after the mould has been lifted out from the frame the vertical part with the bending zone may be lifted in and out in vertical direction through the frame, the curved part may be displaced in horizontal direction, and the means for drawing and bending the bar, which means are designed as a combined pulling, straightening and rolling stand, may separately be moved in and out as an individual constructional unit.

20 An important feature of the plant lies in that the vertical distance between the casting level in the mould and the bottom end of the vertical part of the bar guiding means amounts to from 1.0 to 4.0 m.

The last part of the curved bar guiding means may be designed as non-heated equalization zone.

In order that the invention may be more fully understood these and further features of the invention are explained in greater detail in the following description in connection with the schematical drawing.

30 A water-cooled, straight mould 1 is mounted in a frame 2. Between the frame 2 and the mould 1 there are several rapid connections for the cooling water and for fixing the mould to the frame 2, which, however, are not shown in the drawing. The frame 2 is connected with a mould drive 32 which serves to oscillate the frame 2 and the mould 1 in vertical direction. Two pairs of rolls are fixed to and oscillate together with the mould. The vertical, straight bar guiding part 3 comprising a bearing stand 5 with built in rolls 4 is arranged below the mould 1. At its lower end, in the area of the last pairs of rolls 4, a transitional or bending zone 6 is provided in which the vertical bar guiding part is already slightly bent and leads over the following curved bar guiding means 7. The vertical distance h between the casting level in the mould and the bottom end of the vertical bar guiding part should amount to 1.0 to 4.0 m. Such a provision affords metallurgical advantages. The penetrating casting stream is prevented from damaging the casting shell and the bar solidifies in a uniform manner.

50 When forming the bending zone 6 care has to be taken that at no place of the already partly solidified bar impermissible extensions will occur in any phase of the deflection. At the border line between liquid and solidified layers any elongation should not amount to more than 0.2 to about 0.7 percent, in dependence on the steel quality. In this transitional area the temperature amounts to about 1,400°C. With increasing distance from the solidification front or with falling temperature, respectively, the permissible elongation increases greatly. Thus, the bar is continuously bent in the bending zone 6, i. e., not in steps, and so slowly that no cracks may occur in the bar.

60 According to the invention the straight bar guiding part 3 with the bending zone 6 is formed as an individual, compact constructional unit. It may be lifted out in upward direction after the mould has been lifted out

from the frame. In the drawing the lifted off mould is shown in broken lines and denoted with numeral 1'. The drawing also illustrates in broken lines the bar guiding part 3' after it has been lifted out through the frame. The curved bar guiding part 7 is equally formed as an independent constructional unit. It comprises a curved bearing stand 9 with rolls 8 which may have different diameters, and wheels 10, 10' for displacing the entire constructional unit in horizontal direction on rails 16, 17. The secondary cooling zone extends from the mould to the end of the bar guide 7. It contains supply ducts and spray jets for the cooling water. This bar guiding means comprising two parts is followed by a means for drawing the bar, which means is designed as combined pulling, straightening and rolling stand 12 and comprises a pair of rolls 13, a pair of rolls 14 for straightening the bar and a guiding roll 15. The pair of rolls 13 serves to exert pressure on the bar sufficient to reduce the bar by up to 30 percent. If desired, also the straightening pair of rolls 14 may be used to exert pressure on the bar.

The bar 11 leaves the secondary cooling zone or the curved bar guide 7, respectively, while its temperature is uneven over its entire cross section; with a temperature which is uneven over its entire cross section the bar may be introduced into the combined pulling, straightening and rolling stand where it is shaped by 7 to 20 percent; in this shaping process it is primarily the core zone of the bar that becomes worked. The bar core has an essentially higher temperature, e. g., a temperature that is higher than 900°C, preferably a temperature of 1,200 to 1,300°C. The marginal zone or the surface of the bar 11, however, has a temperature in the range of about 800 to about 1,000°C. If such a bar is subjected to shaping, the core zone of the bar undergoes a substantially higher degree of working than the marginal zone. Thus, when the bar 11 is shaped in the combined pulling, straightening and rolling stand 12 which is arranged after the curved bar guide 7 the core of the bar is densified; this affords a qualitative advantage which becomes particularly obvious when the bar is subjected to further rolling in a conventional second rolling plant to obtain plates. In the second rolling process it is primarily the marginal zone that is shaped so that a final product is obtained that is evenly shaped over its entire cross section.

After shaping of the bar 11 by means of the rolls 13, the shaped bar 11' is directed to be parallel to the mill floor 18 by means of the straightening rolls 14. It is also possible to permit the cast bars to run through the stand 12 without shaping of their cross sections in which case the rolls 13 function only as pulling rolls.

It is also possible to pass the bar through a non-heated equalization zone so that the bar enters into the combined pulling, straightening and rolling stand with 55 a temperature that is highly uniform over its cross section and is shaped by about 10 to 20 percent. Such a non-heated equalization zone 21 arranged as the last part of the curved bar guide 20 is shown in the left part of the drawing. After the temperature has equalized it 60 is primarily the marginal zone of the bar that becomes shaped. This is of great advantage with bars made of rimming steel which have a bubble wreath in their interior below the surface. This bubble wreath would have a heat insulating effect when the bar is re-heated 65

in rolling mill furnaces. Suitably, the equalizing zone 21 forms together with the curved bar guide 20 which is part of the secondary cooling zone a constructional unit 19, which, likewise, is horizontally displaceable and may easily and quickly be exchanged for the bar guide 7 which is in position for operation. The equalization zone may also be designed as a separate constructional unit between the bar guide 7 and the pulling, straightening and rolling stand.

10 The plant may also be provided with a means for the flying exchange of the distributors and the ladles; this means comprises columns 22, which penetrate the pouring platform 23, and horizontally rotatable arms 24, 25 for two ladles and two rotatable arms 26, 27 for 15 two distributors; of these, one ladle 28 and one distributor 30 are always outside the area of the mould 1 as in the position shown. In working position a second ladle which is not shown is positioned by means of the rotatable arm 25 above a second tundish held by the rotatable arm 27. Numeral 29 denotes the bearing trunnions of the ladle 28. In addition, the tundishes may be vertically displaceable along the column 22, so that the drains of the tundishes which, however, are not shown in the drawing may be immersed below the casting level 20 in the mould 1.

What we claim is:

1. A low-head continuous casting plant for the production of slabs preferably having a width of at least 1,000 mm from a continuously cast steel bar, comprising

30 a frame,
a straight, vertically-oriented mould releasably mounted in the frame and being liquid-cooled, driving means attached to the frame and mould for oscillating said frame and said mould,
a first secondary cooling and bar guiding means positioned below the mould and comprising a straight vertical upper section and a curved lower section integral with the upper section for bending the bar having a liquid core and being of such configuration as to provide for continuous bending of the bar, said first secondary cooling and bar guiding means being of such a size to be vertically removable through the frame and arranged below the mould in a manner that the vertical distance between the casting level in the mould and the downstream end of the straight vertical upper section is in the range from 1.0 to 4.0 meters,
a second secondary cooling and bar guiding means positioned downstream from said first secondary cooling and bar guiding means and being substantially arc shaped,

means for horizontally displacing the second secondary cooling and bar guiding means, and
means positioned downstream of the second secondary cooling and bar guiding means for drawing the bar through the first and second secondary cooling and bar guiding means and for straightening and drawing out the bar in horizontal direction.

2. The plant as defined in claim 1 wherein the second secondary cooling and bar guiding means comprises a first liquid-cooled section and a second non-heated equalization section.
